United States Patent Office

Des. 180,943
Patented Sept. 10, 1957

180,943

COMBINATION INJECTOR TEST AND WASH STAND

Stanley E. Franklin, Wilmington, Calif., assignor to Diesel Control Corporation, Denver, Colo., a corporation of Colorado

Application May 10, 1954, Serial No. 30,400

Term of patent 14 years

(Cl. D52—1)

Fig. 1.

Fig. 2.

Fig. 1 is a perspective view of a combination injector test and wash stand, showing my new design.

Fig. 2 is a perspective view thereof from the opposite side, the undisclosed end being substantially the same in appearance as the end shown in the drawing.

I claim:

The ornamental design for a combination injector test and wash stand, substantially as shown and described.
